[57] CLAIM

The ornamental design for a fireplace, substantially as shown and described.

DESCRIPTION

FIG. 1 is a front perspective view of a fireplace showing my new design;

FIG. 2 is a top plan view thereof shown on a larger scale;

FIG. 3 is a front elevational view thereof;

FIG. 4 is an elevational view thereof taken from the end as seen from the right of FIG. 3, the opposite end being a mirror image thereof;

FIG. 5 is a rear elevational view thereof; and

FIG. 6 is a bottom plan view thereof.
